A. M. PASNIK.
VALVED BOTTOM DISPENSING SALT SHAKER.
FILED DEC. 28. 1921.

UNITED STATES PATENT OFFICE.

ALEXANDER M. PASNIK, OF NORWICH, CONNECTICUT.

VALVED BOTTOM-DISPENSING SALT SHAKER.

Application filed December 28, 1921. Serial No. 525,365.

To all whom it may concern:

Be it known that I, ALEXANDER M. PASNIK, a citizen of the United States, residing in the city of Norwich, State of Connecticut, 5 have invented a new and useful Improvement in Valved Bottom-Dispensing Salt Shakers, of which the following is a specification.

The invention is an improvement in valved 10 bottom-dispensing salt shakers or like table articles such as disclosed in my prior Patent, No. 1,366,929 of February 1, 1921. The object of the improvements is to provide a simplified construction, and one which facilitates 15 the filling of the shaker and enables the discharge to be regulated while preserving the other special utilities of this type of device. To this end the invention may be said to consist in the novel device, and the 20 parts, improvements and combinations hereinafter described in preferred embodiment, and more particularly pointed out in the appended claim.

In the accompanying drawings forming a 25 part hereof:

Fig. 1 is a central vertical section showing the spindle and valve in elevation;

Fig. 2 is an elevation on a smaller scale showing the cover in position for filling the 30 shaker through the top;

Fig. 3 is a plan view corresponding to Fig. 2;

Fig. 4 is a central vertical section through an alternative construction of the cap having the spring barrel cup formed integral therewith; and

Fig. 5 is an elevation of the plunger and spring connected together.

The shaker has an upright holder 1, the 40 salt chamber 2 of which has a sloping bottom 3 terminating in a central throat or discharge opening 4. A hollow base or foot 5 below the throat affords a discharge mouth 6.

The throat is normally closed by a tapered 45 plug or valve 7, the lower portion of which seats upwardly against the throat. Above its seating portion 8 this plug is formed with a series of transverse corrugations 9, of diminishing diameters, said corrugations 50 serving to break up lumps when the plug is depressed and to cause a controlled discharge of the salt through the annular outlet between the plug and the throat when the plug is depressed, the plug being worked 55 back and forth if need be to obtain the desired flow. The plug is on the lower end of

a spindle 10, which passes upward through the center of the salt chamber, and has screw-threads 13 on its upper end for connection with a projecting plunger button 11, 60 by means of which the plug is unseated by finger pressure exerted against a spring 12 which acts to close the valve.

In the present improvements the plunger 11 works in, and the spring 12 passes 65 through, a spring barrel or cup 14, which is carried in downwardly projecting relation by the central elevated portion of a removable cover 15. This cover has a depending circumferential rim 16, which slips over a 70 circumferential seat 17 on the top of the receptacle, and in the construction shown in Figs. 1 to 3 its top is formed with a central opening 18, of a size to receive the cup 14 which is inserted downward from the top, 75 the cup having an outturned top flange 19 to retain it upon the cover. The spiral spring 12 is interposed between the bottom of this cup, which has a small central opening for the passage of the spindle 10, and the under 80 part of the button 11, and as clearly shown in Figs. 1 and 5 the spring and button are preferably connected so that they form a unit when the plunger is disconnected from the spindle. This is accomplished in an 85 advantageous manner by forming the button with a bottom nub 20 having flaring sides, whereby an undercut groove is formed for holding the top convolution of the spring. In the modified form of cap 15^a shown in 90 Fig. 4, the cap and the cup 14^a are formed integral.

In either construction the cap is held closed by the downward action of the spring 12, which also acts upwardly to hold the 95 valve plug 7 closed. In order to fill the receptacle through the top, the cover and spring barrel cup are slipped upward on the plunger and spindle until the rim flange 16 clears the top of the receptacle, when the 100 cover and operating parts can be tilted side- 105 wise, as seen in Figs. 2 and 3, thus uncovering a substantial part of the top of the receptacle. This is particularly useful in the case of coarse salt. Fine salt can be filled 110 into the receptacle around the plug by uncovering the receptacle and unseating the plug.

It will be observed that the plunger button 11 is provided with an elongated screw-threaded adjustment bore 21 for the reception of the screw-threads on the upper por-

tion of the spindle 10. This adjustable connection, in conjunction with a stop shoulder 22 on the plunger adapted when depressed to contact with the top of the cover or 5 spring barrel cup, enables the degree of opening of the throat 8 when the plug 7 is unseated to be regulated by the user, thus determining the freedom of flow under different conditions.

10 What is claimed as new is:

A shaker having a receptacle provided with a bottom throat, a downwardly displaceable plug normally closing said throat, a spindle extending upward through the re-

ceptacle, a spring urging the spindle and plug upward, the upper portion of said spindle being screw-threaded, an operating button having an elongated screw-threaded bore adjustably receiving the screw-threaded end of the spindle, and cooperating stop surfaces on the button and receptacle respectively limiting the downward displacement of the plug, the construction being such that screwing the plug up or down on the stem varies the normal distance between said stop surfaces so as to regulate the extent of opening of the plug.

ALEXANDER M. PASNIK.
